PROCESS FOR PRODUCING NICOTINIC ACID FROM ACRYLONITRILE

Manuel M. Baizer, St. Louis, Mo., assignor to Monsanto Company, a corporation of Delaware
 No Drawing. Filed Dec. 18, 1963, Ser. No. 331,355
 6 Claims. (Cl. 260—295.5)

The present invention concerns a procedure for preparing nicotinic acid from acrylonitrile. The invention is also directed to particular steps of the procedure and to one of the intermediate products obtained in the procedure, viz. 1,8-diamino-4-aminomethyloctane.

Nicotinic acid, i.e., pyridine-3-carboxylic acid, is a known compound of recognized value as an anti-pellagra vitamin. It occurs in liver, yeast, etc., and can be prepared by oxidation of nicotine extracted from tobacco leaves.

It is an object of the present invention to provide a source of nicotinic acid. It is a further object to provide a procedure for converting acrylonitrile to nicotinic acid. Acrylonitrile is an abundantly available, inexpensive industrial raw material produced by several different commercial processes. It has not previously been proposed, however, to convert acrylonitrile to nicotinic acid.

In accordance with the present invention acrylonitrile is converted to nicotinic acid by a series of steps involving reductive trimerization of the acrylonitrile to 1,3,6-tricyanohexane, reduction and cyclization to 3-(4-aminobutyl)-pyridine, dehydrogenation to 3-(4-aminobutyl)-pyridine, and oxidation to pyridine-3-carboxylic acid. In the reduction step, 1,8-diamino-4-aminomethyloctane is generally found along with the 3-(4-aminobutyl)-piperidine but can be cyclized to the piperidine under the reaction conditions.

Representative procedures in accordance with the invention can be pictured:

In the first step of the present invention acrylonitrile is reductively trimerized to tricyanohexane. This step can be conducted electrolytically as taught in my copending application S. N. 260,853 by electrolyzing the acrylonitrile in contact with a cathode in an electrolyte solu-

2

tion. This reaction can be conducted under general electrolysis conditions but to direct the reaction to trimers other than dimers, only limited amounts of proton donors such as water and acetonitrile should be present, although some proton donor is needed to avoid direction of the reaction to higher polymers, and it is also desirable to exclude free-radical catalysts or anions capable of generating anionic polymerization of acrylonitrile. Any other reductive means capable of reductively trimerizing acrylonitrile to 1,3,6-tricyanohexane can be employed in this step of the process.

The tricyanohexane is then reduced by reducing means capable of reducing cyano groups to amino groups. Hydrogenation procedures are particularly suitable.

The hydrotrimer, i.e., 1,3,6-tricyanohexane, will generally be obtained to some extent even if large amounts of proton donor are present during the electrolysis, but it is preferred to maintain such amounts relatively low in order to obtain suitable yields. The electrolysis is preferably conducted in a catholyte compound of salt, acrylonitrile, a proton source and possibly also a co-solvent (which can also be the proton source). When water is the proton donor, it preferably ranges from 3% or so up to about 20% by weight of the catholyte. The acrylonitrile often constitutes 20 to 40% by weight of the catholyte, and the electrolyte salt often 40 to 70% by weight of the acrylonitrile and salt, although the percent of the salt is often lower when no co-solvent is present. Acetonitrile can also be employed as a proton donor. Further explanations of various procedures and conditions for obtaining the 1,3,6-dicyanohexane are set forth in my aforementioned copending application, S. N. 260,853.

Example 1

An electrolysis was conducted with a catholyte of 60 grams tetraethylammonium p-toluenesulfonate, 3 grams water and 160 grams acrylonitrile, and an anolyte of 30 ml. 82% methyltritylammmonium methylsulfate diluted with 20 ml. water. A current of 1.5 to 2.0 amperes was passed for 3.5 ampere-hours. The catholyte was diluted with water and extracted with methylene dichloride. A liquid residue isolated from the extracts was distilled, a 4.3 gram fraction having B.P. 150-180° C./0.25 mm., n_D^{25} 1.4670, M.W. 145.

Anal.—*Found:* C, 65.76; H, 7.15; N, 24.86.

The high boiling oils obtained in different electrolyses of acrylonitrile were collected. One portion boiling 134-178°/0.2 mm. was isolated by extracting the catholyte of Example 6 with methylene dichloride. Another was obtained from electrolysis of acrylonitrile in 91% quaternary ammonium sulfonate without a co-solvent. Still other portions were obtained in the residue of electrolytic adiponitrile preparations. The oils were combined and then separated by distillation, one liquid boiling 186-200°/0.2 mm. and the second, 264/0.05 to 288/0.18 mm. Analysis indicated the first to be a hydrotrimer, 1,3,6-tricyanohexane, which was confirmed by preparation of derivatives.

Anal.—*Calc'd* for $C_9H_{11}N_3$: C, 67.05; H, 6.88; N, 26.07; mol. wt., 161.2. *Found:* C, 66.81; H, 7.02; N, 24.72.

Hydrolysis yielded 1,3,6-tricarboxyhexane, M.P. 112° compared to the reported 111-112° C.

Anal.—*Calc'd* for $C_9H_{14}O_6$: C, 49.54; H, 6.47; neutr. equiv. 72.7. *Found:* C, 49.40; H, 6.55; neutr. equiv. 73.2.

A sample of the tricarboxyhexane showed no depression in melting point when mixed with 1,3,6-tricarboxyhexane obtained by the novel procedure of preparing diethyl alpha-(3-cyanopropyl), alpha-(2-cyanoethyl) malonate from alpha-(3-cyanopropyl) malonate and acrylo-

nitrile, and hydrolyzing with concentrated hydrochloric acid. The higher boiling oil above was shown by analysis to be an acrylonitrile hydrotrimer, which could be formulated as 1,3,5,8-tetracyanoctane or 1,3,6,8-tetracyanoctane. The tetraethyl esters corresponding to both of these structures were independently prepared and compared with the tetraethylesters obtained by hydrolysis and esterification of the hydrotrimer, and both nuclear magnetic resonance and vapor phase chromatographic examination showed the esters from the hydrotrimer to be mixtures of those obtained from the two structures. The 1,3,6,8-tetracarboxyloctane was obtained by cyanoethylating tetraethyl 1,1,4,4-butanetetracarboxylate with acrylonitrile in caustic methanol to form tetraethyl 1,4-bis(2-cyanoethyl)-1,1,4,4-butanetetracarboxylate, hydrolyzing with concentrated hydrochloric acid, esterifying with ethanol sulfuric acid, and fractionating, 166-184°/0.08-0.10 mm. n_D^{25} 1.4480.

Anal.—Found: C, 59.41; H, 8.43.

The 1,3,5,8-tetracarboxyloctane was obtained by base catalyzed addition of diethyl alpha-(2-cyanoethyl) malonate to methyl alpha-(3-cyanopropyl) acrylate to form 1,8-dicyano-3,3-dicarbethoxy-5-carbmethoxyoctane, followed by hydrolysis with concentrated hydrochloric acid and esterification with ethanol sulfuric acid. Upon distillation the vapor fraction was obtained at 180°/0.3 mm. to 182°/0.25 mm., n_D^{25} 1.4770.

Anal.—Found: C, 59.46; H, 8.21.

The 1,4-bis(2-cyanoethyl)-1,1,4,4-butanetetracarboxylate intermediate above was crystallized from t-butyl-alcohol, M.P. 93-94°.

Anal.—Calc'd for $C_{22}H_{32}N_2O_8$: C, 58.39; H, 7.13; N, 6.19. Found: C, 58.24; H, 7.17; N, 6.15.

Example 2

To a 300 ml. bomb were charged 40 grams of acrylonitrile hydrotrimer (1,3,6-tricyanohexane), 70 grams anhydrous ammonia and 3 grams Raney cobalt (under ethanol). The bomb was heated to 150° C. and pressured to about 3000 p.s.i. with hydrogen, and rocked under these conditions for about 24 hours with hydrogen being added at intervals to maintain pressures of about 3000 to 4000 p.s.i. The reaction mixture was distilled with an 18" Vigreux column, a 14.5 gram fraction being obtained at 75-90° C./0.2 mm., n_D^{27} 1.4822 and an 18.4 gram fraction of 1,8-diamino-4-aminomethyl octane at 98.5-103° C./0.20-0.25 mm.; n_D^{27} 1.4848. The residue was combined with the reaction mixture of a duplicate hydrogenation, and distilled, a lower boiling fraction of 14.1 grams being obtained at 71-95° C./0.20-0.25 mm., and a 9.8 gram triamine fraction at 102-106° C./0.30-0.35 mm. The lower boiling fractions of the distillations solidified upon cooling. A sample of the solid was dissolved in ethanol, treated with a few drops of concentrated hydrochloric acid, evaporated to dryness, recrystallized from alcohol and dried, M.P. (capillary) 226-228° C. The reported value [J. Am. Chem. Soc., 67, 1258 (1945)] for 3-(4-aminobutyl)piperidine dihydrochloride is 228.8-230° C.

Anal. for $C_9H_{22}N_2Cl_2$.—Calc'd: C, 47.16; H, 9.68; N, 12.22. Found: C, 46.05; H, 9.65; N, 11.46.

Another sample was converted to the p-toluenesulfonamide salt, $C_{23}H_{32}N_2S_2O_4$, and recrystallized from water, M.P. (capillary) 146-147° C. (reported 143-144° C.).

Example 3

A 300 ml. bomb was charged with Raney cobalt, 3 grams, 1,8-diamino-4-aminomethyloctane, 21 grams, and 20 grams of anhydrous ammonia. The bomb was pressured with hydrogen and heated at 150° C. for about three hours, pressures of about 3750 p.s.i. being attained. The product was distilled through an 18 inch Vigreux column, a 4.2 gram fraction being obtained at 63-67° C./0.06-0.10 mm., which had infrared spectra and refractive index identical to that of 3-(4-aminobutyl)piperidine, the

conversion being 25%. An 11 gram fraction of the starting triamine was recovered in the distillation.

Example 4

To 6.5 gram portion of the 3-(4-aminobutyl)piperidine in benzene, 9.1 grams of acetic anhydride was slowly added to acetylate the two amino groups. After the exothermic reaction subsided the reaction mixture was refluxed for 1 hour and volatile material was then evaporated to leave a syrup which was dissolved in benzene, washed with bicarbonate solution and with water, and dried over magnesium sulfate. The solvents were removed to leave 9 grams of the diacetylated syrup. The syrup was mixed with a gram of 10% palladium on carbon catalyst and heated at 200-250° C. for about four hours as about 1135 ml. of gas was collected. The reaction mixture was treated with methylene chloride, and filtered, the catalyst being washed thoroughly with methylene chloride. The methylene chloride was removed by warming over a water bath to leave 6.9 grams of liquid having a strong pyridine odor [theory for 3(4-acetylaminobutyl)pyridine is 7.2 grams]. To the product under a reflux condenser, 75 ml. of concentrated nitric acid was slowly added, and following the exothermic reaction the mixture was slowly warmed to 80° and maintained at such temperatures for about 12 hours. The product was evaporated nearly to dryness, dissolved in hot water, treated with charcoal, filtered, concentrated by evaporation, chilled in ice and about 1 gram of crystals obtained by filtration. The mother liquor was further concentrated and a second 1 gram crop of crystals obtained. The combined crystals were dissolved in hot water, treated with $Na_2HPO_4 \cdot 7H_2O$, the pH adjusted to 3-4 with hydrochloric acid, concentrated, chilled in ice and a yellow-white solid separated by filtration. The solid was air-dried, digested with alcohol, decanted through a filter, concentrated to yield a crop of crystals, M.P. (capillary) 225-232° C. A second crop of crystals of lower melting point was possibly contaminated with nitrate. The first crop was recrystallized from alcohol, M.P. (capillary) 232-236° C., and had an infrared spectrum identical to that of nicotinic acid.

Example 5

A 1 liter bomb was charged with 30 grams of the electrolytically produced hydrotrimer of acrylonitrile, 2 grams Raney cobalt in 25 ml. ethanol, and 106 grams ammonia. The hydrotrimer was charged first, followed by the catalyst slurry and the bomb was then sealed and cooled in an acetone-Dry Ice bath and the ammonia was introduced and the bomb allowed to come to room temperature and pressured to 600 p.s.i. with hydrogen. The bomb was then heated to about 140° C. with periodic addition of hydrogen, pressures of 4000 p.s.i., being attained, and maintained under pressure overnight. The bomb was vented and the product taken up in ethanol. The catalyst was removed by filtration and the alcohol by vacuum to leave a 33 gram residue. The product was distilled, combined with product of a similar hydrogenation over pelleted cobalt catalyst, and then redistilled through a Todd column, and 11.7 gram fraction of 1,8-diamino-4-aminomethyloctane being obtained at 161-163°/4 mm., n_D^{25} 1.4883. Infrared spectra indicated $-NH_2$ groups but no $-CN$ groups.

Anal.—Calc'd for $C_9H_{23}N_3$: C, 62.43; H, 13.29; N, 24.28. Found: C, 62.15; H, 13.36; N, 23.27.

In general reduction procedures suitable for reducing cyano groups to amino groups can be employed in the reduction step. Catalytic hydrogenation is the usual method, metallic catalysts usually being employed. Nickel catalysts, e.g., nickel on kieselguhr or Raney nickel, can be employed. Platinum, platinum oxide and palladium catalysts are also suitable, e.g., Adams platinum catalyst or palladium on cobalt or charcoal. The hydrogenation is usually conducted at temperatures of 100-150° C., al-

through higher or lower temperatures can be employed, particularly, for example, if a catalyst such as a Raney nickel especially adapted for use at low temperature and pressure is employed. The pressures employed are those suitable for catalytic hydrogenation which are superatmospheric pressures and generally above 100 p.s.i. and usually from several hundred p.s.i. up to several thousand p.s.i. or higher, e.g., 500 p.s.i. to 5000 p.s.i. The formation of secondary products can be suppressed to some extent by employing relatively large amounts of catalysts to effect rapid hydrogenation. The use of ammonia during the hydrogenation serves to direct the hydrogenation toward the open-chain triamine at the expense of cyclization to the substituted piperidine. However, unless very large amounts of ammonia are used, some of both products are ordinarily obtained. For example, utilizing, on a weight basis, from less than an equivalent amount of ammonia to twice the amount of ammonia compared to the 1,3,6-tricyanohexane, both the open-chain triamine and the substituted piperidine are obtained, whereas, when the amount of ammonia is three-times or more by weight that of the tricyanohexane, the product is practically exclusively the open-chain triamine. The cyano groups can also be reduced by other known means for reducing cyano groups to amino groups, e.g., reduction with sodium and alcohol or with lithium aluminum hydride. The 1,8-diamino-4-aminomethyloctane obtained by hydrogenation or other reduction, can, if desired, be converted to the 3-(4-aminobutyl)-pyridine by treating the referred-to octane under hydrogenation conditions taught herein for the production of 3-(4-aminobutyl)-piperidine from tricyanohexane, which are in general catalytic hydrogenation condition, optionally in the presence of ammonia.

The dehydrogenation step can be conducted according to ordinary dehydrogenation procedures for preparing aromatic compounds. In general this involves heating the substituted piperidine compound with a catalyst. The usual hydrogenation catalysts can be used for such dehydrogenations. Platinum and palladium catalysts are very suitable, generally being employed on the usual supports. Nickel catalysts can also be used, as can various metal oxide catalysts, and metallic catalysts in general. Various temperatures can be employed for the dehydrogenation, the advantage of particular temperatures depending upon the catalyst. For example temperatures from less than 100° C. to more than 350° C. can be employed, as can other higher and lower temperatures.

In the oxidation step, the aminobutyl group can be oxidized by methods commonly used to oxidize alkyl groups to carboxyl groups, e.g., oxidation with nitric acid, alkaline permanganate or gaseous oxygen under the usual conditions, or by employing other oxidizing agents.

The nitric acid can be added in concentrated form to the pyridine compound, followed by warming, e.g., from 50 to 100° C. or so to complete the oxidation, but dilute nitric acid or more or less rigorous temperature conditions can also be employed. Other known procedures for oxidizing alkylated benzenes to benzoic acids can suitably be employed in the oxidation step.

What is claimed is:

1. The method of preparing nicotinic acid which comprises reductively trimerizing acrylonitrile to tricyanohexane, hydrogenating the cyano groups, heating with dehydrogenation catalyst to obtain 3-(4-aminobutyl)-pyridine, and oxidizing the aminobutyl group to a carboxyl group to obtain nicotinic acid.
- 10 2. The method of preparing nicotinic acid which comprises electrolyzing a salt solution of acrylonitrile in contact with a cathode to obtain 1,3,6-tricyanohexane, hydrogenating the 1,3,6-tricyanohexane in the presence of ammonia to obtain 3-(4-aminobutyl)-piperidine, heating with dehydrogenation catalyst to obtain 3-(4-aminobutyl)-pyridine and oxidizing to nicotinic acid.
- 15 3. The method of claim 2 in which the hydrogenation also produces 1,8-diamino-4-aminomethyloctane which is converted to 3-(4-aminobutyl)-piperidine by continuing the hydrogenation conditions.
- 20 4. The method of claim 2 in which the amino groups are acylated prior to the dehydrogenation.
- 25 5. The method of preparing nicotinic acid which comprises hydrogenating the cyano groups of 1,3,6-tricyanohexane and heating with dehydrogenation catalyst to obtain 3-(4-aminobutyl)-pyridine, and oxidizing the aminobutyl group to a carboxyl group to obtain nicotinic acid.
- 30 6. The method of preparing nicotinic acid which comprises electrolyzing acrylonitrile in a quaternary ammonium aromatic sulfonate solution containing only a small amount of water to obtain 1,3,6-tricyanohexane, hydrogenating the cyano groups over a metallic hydrogenation catalyst at temperatures of about 100° to 150° C. in the presence of ammonia with hydrogen pressures of 100 to 5000 p.s.i., and dehydrogenating by heating over a dehydrogenation catalyst to obtain 3-(4-aminobutyl)-pyridine and oxidizing with nitric acid to nicotinic acid.
